ATTORNEY.

UNITED STATES PATENT OFFICE.

RICHARD A. PHELAN AND HAROLD A. WEGUELIN, OF ST. LOUIS, MISSOURI.

FUME GENERATOR.

1,405,802.

Specification of Letters Patent. Patented Feb. 7, 1922.

Application filed December 13, 1919. Serial No. 344,576.

To all whom it may concern:

Be it known that we, RICHARD A. PHELAN and HAROLD A. WEGUELIN, citizens of the United States, and residing in the city of 5 St. Louis and State of Missouri, have invented certain new and useful Improvements in Fume Generators, of which the following is a specification.

Our invention relates to an improved fume 10 generator and more particularly to a device for generating fumes from iodine crystals to be used for chemical, medical and therapeutic purposes and is a distinct and practical improvement to overcome certain objections to, and defects in, the present known forms of fume generators, or vaporizers.

An object of our present invention is to provide a transparent device for generating fumes from iodine crystals to be used for 20 chemical purposes by changing the almost insoluble iodine crystals into iodine fumes which fumes are freely soluble in alcohol, or oils without the addition of other chemicals.

A further object of the invention is to 25 provide a device for generating non irritant fumes from iodine crystals to be used internally in treating a mucous membrane, such as the ear, nose and throat and for external purposes in treating open wounds, 30 extensive burns and the like.

A further object of our present invention is to provide a transparent device of this class made of glass, which will readily generate fumes from iodine crystals, or other 35 volatile chemicals when heat is applied to the device, which will permit the fumes to be seen while being generated and to permit the generated fumes to be visible until they have been discharged.

40 A further object of the invention is the provision of means to receive the crystals, while being generated into fumes, and prevent dense accumulations from being driven out of the device with the fumes.

45 A still further object of the invention is to provide an all glass generator, which consists of a minimum number of parts, that can be readily assembled and disassembled, convenient and practical to handle 50 and operate and which will be highly efficient for the purposes intended.

With the above and other objects in view, the invention consists in certain novel features of construction, arrangement and combination of parts hereinafter fully described 55

and finally pointed out in the claim hereto appended.

Referring to the accompanying drawings forming a part of this specification where-in like characters of reference denote similar parts throughout the several views:

Fig. 1, is a longitudinal sectional view of a fume generator constructed in accordance with our invention.

Fig. 2, is a sectional view, partly in side 65 elevation of the medicament retainer and fume generating section of the device.

Fig. 3, is a sectional view, partly in side elevation of the fume filtering section carried at the discharge end of the fume generating 70 section.

Fig. 4, is a side elevation, partly in section of the fume discharging or nozzle section of the device.

Referring to the drawings, the reference 75 character 1 indicates a suitable rubber bulb having a nipple 2 provided with an air discharge passage 3. The opposite end of the bulb is provided with an air inlet opening 4 provided with a suitable check valve 5.

6 indicates a glass fume generating tube section having a contracted tubular neck 7 at one end. A suitable hose connection 3¹ connects the nipple 2 with the neck 7 of the fume generating tube 6. The fume generating tube is provided with an enlarged section 8 to hold the iodine or other medical crystals designated 9. The fume generating tube is provided with a contracted tubular neck 10 which is covered with a suitable 85 packing 11.

12 indicates a glass tubular member having a contracted neck portion 13. The neck portion of the tubular member 12 is provided and encircled with a suitable packing 14. 95 The neck 13 and packing 14 are inserted into the contracted tubular neck 10 of the fume generating tube so that the neck will extend slightly into the generating chamber 15 of the fume generating tube 6, as clearly 100 shown in Fig. 1. A suitable filler, such as cotton 16 to act as a fume strainer or filter, is inserted into the tubular member 12.

17 indicates a glass tubular nozzle section which has telescopic connection with 105 the packing 11 which covers the contracted tubular neck portion of the fume generator tube 6. The tubular nozzle section 17 is contracted as at 18 and provided at its outer or discharge end with a suitably shaped 110

preferably tapered nozzle end 19 having a fume discharge opening 20. The tubular member 12 is positioned with the tubular nozzle member 17 when the device is assembled, as clearly shown in Fig. 1.

21 indicates a suitable alcohol lamp or other device which is capable of producing a small flame designated 22 for heating the fume generating tube 6 to heat the crystals 10 so they will throw off fumes, which fumes are to be discharged from the generating chamber through the straining or filtering tube and finally through the nozzle member of the device by pressing on the bulb 1 15 to force air through the device for discharging the generated fumes, as is manifest. The operation of the device, after it has been assembled, as shown in Fig. 1, is as follows:

20 The chemical crystals 9 are placed into the generating tube before the fume strainer section and nozzle are assembled. The crystals 9 are adapted to lie in the bottom of the enlarged section 8 of the tube 6. The device 25 is then passed horizontally over the flame 22 until the fumes generated from the crystals gain the desired strength. The bulb 1 is then pressed together and the fumes through this pressing operation of the bulb 30 are discharged through the discharge opening 20 of the nozzle member and directed upon or into the effected tissues, or inhaled.

It is evident from the foregoing description that the fume generating and discharging device herein described and illustrated 35 is simple in operation, that the color and density of the fume generated can be easily controlled owing to the fact that the entire device being made from glass the fumes are 40 visible at all times until discharged and further that owing to the enlarged section 8 of the generating tube and the axially disposed strainer section there can be no ash discharged with the fumes out of the discharge opening 20. It will be further observed that there being no metal parts with

which the generated fumes come in contact that no foreign chemical action can take place so that only the chemically pure generated fumes can be discharged from the device which are always under control as to 50 color and density.

The many advantages of the herein described invention will readily suggest themselves to those skilled in the art to which it 55 appertains, such as doctors, nurses and chemists.

We do not wish to be understood as having limited ourselves to the details of construction shown and described, but desire to have 60 it understood that the invention we have shown in the drawings is merely illustrative, as it is manifest that various minor changes may be made in the exact construction and particular arrangement of parts without 65 departing from the spirit of our invention, hence we reserve the right to make any such changes or modifications as may fairly fall within the scope of the appended claim when fairly construed. 70

What we claim is:

In combination, a transparent generator tube having an enlarged body portion to hold crystals to be generated into fumes by applying heat to the generator tube, a transparent tubular member mounted in one end of the generator tube and extending into the generating chamber thereof, filtering means carried by the transparent tubular member, a transparent tubular nozzle having a discharge opening in one end, said nozzle having connection at one end with one end of said generator tube and a rubber air bulb having connection with the opposite end of said generator tube for discharging the generated fumes by compressing the bulb with the fingers. 75 80 85

In testimony whereof, we have hereunto signed our names to the specification.

RICHARD A. PHELAN.
HAROLD A. WEGUELIN.
